UNITED STATES PATENT OFFICE.

CHARLES L. BELLAMY, OF ARLINGTON, NEW JERSEY.

DESIGN FOR A PADLOCK-CASE.

SPECIFICATION forming part of Design No. 11,763, dated May 4, 1880.

Application filed April 15, 1880. Term of patent 7 years.

To all whom it may concern:

Be it known that I, CHARLES L. BELLAMY, a citizen of the United States, residing at Arlington, Hudson county, New Jersey, have 5 originated a new and ornamental Design for a Padlock, of which the following is a specification, in connection with the accompanying drawing.

My present design is related to that kind of 10 design which embodies the lines of a horseshoe form in the face of a padlock, on which a previous patent was granted me June 24, 1879; and my present invention lies in a design of this character possessing a novel and pleasing 15 effect.

The figure in the drawing presents a view of the front or ornamental face of a padlock embodying my new design.

As seen in the illustration, I design the body 20 of the padlock in about the usual ovate or horseshoe shape; but I form around the margin thereof a flat band following the contour of the ovate body, and of a distinct width, so as to present the appearance of a frame around 25 the center of the padlock, having the general shape of a horse's shoe, or that of a truncated egg-shaped oval. The marginal band by preference does not extend entirely around the outline of the ovate body, but terminates at the 30 top, as shown, and the flat face of the band may be studded with projections representing the calks and nail-heads in a horse's shoe, when it is desired to obtain the appearance of a horse's shoe; but while this is generally preferable it is not essential to my design. Upon 35 the center of the body a panel is formed, which is inclosed by the marginal band for which it serves as a frame, so that these two combined

features of marginal band and central panel thus effectually relieve the face of the padlock 40 of objectionable flatness and impart thereto an attractive appearance. The central panel may be raised above or depressed below the flat marginal band; but it is preferably depressed, and it may contain a motto or some 45 ornamental figuring. When, however, the marginal band is studded to represent a horse's shoe, I prefer to figure the surface of the central panel so as to represent the frog of the horse's hoof, and thus harmonize with the inclosing margin; but the essential feature of my design consists of an ovate body having a flat 50 marginal band inclosing a central panel, and the superficial figuring of the band or panel may hence be modified somewhat in its details 55 without departing from the essential effect of my design. The hasp of the lock arches over from one limb of the marginal band to the other in an unbroken line therewith on the outer edge, thus giving the face of the lock a 60 more smooth and harmonious effect, and the key-hole or other apertures of the lock are preferably made on the reverse or concealed side of the body, so as to avoid the distracting 65 effect of the same upon the ornamental side.

What I claim as my invention is—

A design for a padlock, consisting of a truncated ovate body, with a flat marginal band encircling or partly encircling the face thereof, and a central panel upon said face, inclosed by 70 the said band, substantially as herein described and illustrated.

CHARLES L. BELLAMY.
